(57) **CLAIM**

The ornamental design for a light-emitting diode for illuminating an object, as shown and described.

DESCRIPTION

The article is a light-emitting diode for illuminating an object, and it may, for example, be incorporated into a camera or the like and used to illuminate an object when taking a photograph.

FIG. 1 is a perspective view of a light-emitting diode for illuminating an object in accordance with the present design, as viewed from above;

FIG. 2 is a perspective view thereof as viewed from below; FIG. 3 is a front view the rear view being a mirror image thereof;

FIG. 4 is a top plan view thereof;

FIG. 5 is a bottom plan view thereof;

FIG. 6 is a right side view the left side view being a mirror image thereof;

FIG. 7 is a sectional view taken along the 7—7 line in FIG. 3; and,

FIG. 8 is a sectional view taken along the 8—8 line in FIG. 6.
